TWO CYCLE ENGINE

Leo G. Collins, Lancaster, N. H.

Application December 16, 1932, Serial No. 647,649

1 Claim. (Cl. 123—50)

This invention relates broadly to internal combustion engines and has particular reference to gasoline engines of the two cycle type.

The invention aims to provide an internal combustion engine of the two cycle type that has fewer parts than similar engines now commonly used; is characterized by an arrangement and combination of elements tending to eliminate vibration; and wherein the thrust of the explosion is absorbed through the connecting rods and crank shaft at opposite points at the same time so that torque at the engine support is substantially precluded.

The invention together with its numerous objects and advantages, will be best understood from a study of the following description, taken in connection with the accompanying drawings wherein:

Figure 1 is a longitudinal sectional elevational view taken through the engine the power cylinder being shown at the end of its power stroke.

Figure 2 is a view similar to Figure 1 the power cylinder being shown at the limit of its compression stroke.

Figure 3 is a sectional elevational view at right angles to Figure 2 the parts being shown in a position corresponding to the position of the parts in Figure 2.

Figure 4 is a view taken at right angles to Figure 1, the parts of Figure 4 being shown partly in section and partly in elevation, and in position corresponding to the positions shown in Figure 1.

Figures 5, 6, and 7 are sectional views taken substantially on the line 5—5, 6—6, and 7—7 respectively of Figure 1.

Figure 8 is a sectional view taken substantially on the line 8—8 of Figure 2.

Referring to the drawings in detail it will be seen that the internal combustion engine embodying the features of the present invention, includes among other parts, a crank case 10 having a power cylinder 11 rising therefrom; and cylinder 11 at its upper end is enlarged diametrically to provide a fuel receiving chamber 12 into which fuel, from the carburetor (not shown) is admitted through an intake port 13 provided in the top of the chamber and controlled by a poppet valve 14.

There is also provided about the cylinder 11 a chamber 15 for the circulation of a cooling medium such as water or the like.

Suitably journaled in the crank case 10 is a crank shaft 16 provided with a pair of cranks

or throws 17 and a third crank or throw 18. The cranks or throws 17 are disposed at about one hundred and eighty degrees relative to the crank or throw 18.

Arranged to reciprocate within the power cylinder 11 is a compression cylinder 19 that is closed at its upper end and opened at its lower end. At said upper end the cylinder 19 is provided with a piston 20 arranged to reciprocate within the chamber 12. Cylinder 19 is connected with the cranks or throws 17 through the medium of connecting rods 21, one end of which rods are suitably connected with lateral pins 22 projecting from the cylinder 19 intermediate the ends of the cylinder, and operating in slots 23 provided in the cylinder 11.

Arranged to reciprocate within the cylinder 19, relative to said cylinder is a power piston 24 that is suitably connected through the medium of a connecting rod 25 with the throw or crank 18.

When the fuel in the chamber 12 is compressed, the same is forced from the chamber through a passage 26 provided in the peripheral wall of the chamber adjacent the inlet port 13, and from the passage 26 the fuel passes through a passage 27 provided in the peripheral wall of the cylinder 19, and as shown in Figure 1, passage 27 at its upper end opens laterally through the piston 20, while at its lower end the passage 27 opens into the cylinder 19 at a point below the transverse median of the cylinder.

The cylinder 19 in a relatively opposite side thereof, and in a plane above the lower end of the passage 27 is provided with an outlet or scavenging port 28 that is adapted to register with a scavenging or outlet port 29 provided in the wall of the power cylinder 11 when the parts are in the position shown in Figure 1, that is to say when the cylinder 19 is at the limit of its upstroke, and the power cylinder 24 is at the limit of its down or power stroke.

The cylinder 19 adjacent its upper end is also provided with a suitable spark plug hole in which is arranged a spark plug 30. Suitably mounted on the exterior of the power cylinder 11 is a spring contact member 31 with which the spark plug 30 engages for igniting the fuel when the parts are in the position shown in Figure 2, that is when the cylinder 19 is at the limit of its downstroke, and the power piston 24 is at the limit of its compression stroke.

There is also provided on the top of the power piston 24 a baffle 32 that is so arranged as to be in suitable position relative to the outlet end of

- the passage 27 when the parts are in the position shown in Figure 1 so as to cause the incoming fuel to spread in a manner to insure proper combustion.
- 5 The operation is thought to be clear from a consideration of the drawings. As cylinder 19 and power piston 24 move from the position shown in Figure 1 to the position shown in Figure 2 a fuel mixture is taken from the carbureter (not shown) through the port 13, valve 14 being open as shown in Figure 2 into the chamber 12, where on the next half revolution, the fuel is compressed, cylinder 19, and piston 24 moving from the position shown in Figure 15 2 or 3 to the position shown in Figure 1 or 4. As the gas is compressed, it escapes from the chamber 12 through the passages 26 and 27 into the cylinder 19 and as the cylinder 19 moves down, and the piston 24 moves up to the position shown in Figure 2, the fuel in the cylinder 19 is compressed. The downward movement of the cylinder 19 to the position shown in Figure 2 brings the spark plug 30 into engagement with the contact 31 whereby an electric spark is developed for igniting the fuel compressed between the tops of the cylinder 19 and the piston 24. Obviously upon explosion of the fuel cylinder 19 is forced upwardly and piston 24 forced downwardly on its power stroke.
- 30 It is of course to be understood, that a suitable carbureter, together with suitable oiling and

electric systems will be employed, but since they are not of the essence of the invention and any well known type of same may be employed, a showing of the same in the drawings has been dispensed with.

Even though I have herein shown and described the preferred embodiment of the invention, it is to be understood that the same is susceptible of further changes, modifications and improvements coming within the scope of the 10 appended claim.

Having thus described my invention, what I claim as new is:

In an internal combustion engine of the character described comprising a stationary outer cylinder, a piston operative in the said cylinder, said piston being provided with a depending cylinder, a guide for the depending cylinder, said guide having a water jacket being adapted to support the said stationary cylinder, a spark 15 plug projecting into the depending cylinder immediately under the piston thereon and having an outwardly projecting electrode, and a spring contact mounted upon the said water jacket, said outer cylinder having an opening in the 20 lower portion thereof through which air can pass and into which the upper portion of the spring projects into the stationary cylinder in the path of the electrode of the said spark plug.

30 LEO G. COLLINS.
